UNITED STATES PATENT OFFICE.

GEORGE F. KOENIG, OF LE SUEUR, MINNESOTA.

HOISTING DEVICE.

No. 847,667.

Specification of Letters Patent.

Patented March 19, 1907.

Application filed October 8, 1906. Serial No. 337,924.

To all whom it may concern:

Be it known that I, GEORGE F. KOENIG, a citizen of the United States, residing at Le Sueur, in the county of Lesueur and State of Minnesota, have invented certain new and useful Improvements in Hoisting Devices, of which the following is a specification.

My invention has relation to new and useful Improvements in hoisting-machines, and while it is primarily intended and is especially designed to hoist soil, gravel, and manure it may be used in all cases where hoisting is to be done.

The object of my invention is the production of a machine of this character that may be easily moved from place to place, made stationary, and serve any of the functions expected of a machine of this character in an expedient and improved manner, the machine being very simple and very substantial in construction.

In the accompanying drawings, in which like parts are designated by like characters throughout the several views, Figure 1 is a side elevation of my invention. Fig. 2 is a top plan view cut on the line X X of Fig. 1. Fig. 3 is a vertical longitudinal sectional view. Fig. 4 is a rear end view, the bucket and means for suspending same removed. Fig. 5 is a detail view of my invention, showing a transverse section of the platform with part broken away, one of the top brace-beams of the frame, part broken away, one of the guard-dogs employed to guard against accidental dropping of the platform when raised, and part of the means for operating and controlling said guard-dog. Fig. 6 is a bottom plan view of the platform. Fig. 7 is an enlarged bottom plan view of a section of the platform. Fig. 8 is a side edge view of the platform shown partly in section, showing the trap-doors open and the arrangement of the pulleys and chains for opening and closing said doors.

My invention is described as follows:

The numeral 1 represents my invention, which consists of a frame comprising four or more vertical beams 2, secured together at their upper ends by longitudinal side beams 3. The lower ends of the foremost of said vertical beams are connected by a transverse beam 4. The frame is of sufficient height and width to allow a three-horse team to pass under a platform thereof when the same is elevated in the manner hereinafter described. Said frame is mounted on a truck

consisting of a rear axle 5, mounted on wheels 6, and front axle 7, mounted on wheels 9 and pivoted, by means of a king-bolt 10, to said front transverse beam 4, the said king-bolt passing through central vertical perforations in said transverse beam and axle 7, its lower end protruding somewhat below the face of said axle and passing through the front perforated end of a reach-support 11, secured to the lower and inner faces, respectively, of said axle 7 and beam 4. Movable reaches 12 are removably secured at their rear ends to said rear axle 5 and are removably secured at their front ends to said reach-support 11 by a pin 13 or other equivalent means.

A platform 14, provided with two centrally-located trap-doors 15 and 16, is adjustably suspended from the frame of my invention, said platform being constructed of plank or other suitable material of sufficient strength to support a load for a three-horse team. Said platform is provided at its sides with longitudinal beams 17 and at its front and rear ends with transverse beams 18, which are preferably secured at their ends to the tops of said beams 17. Secured to the outer faces of said beams 17 intermediate of their lengths are bearings 19, in which are journaled pulleys 20, and secured to the ends of the rearmost of said doors, near its inner side edge, are bearings 21, in which are journaled pulleys 22. Journaled in suitable bearings 23, secured to the under sides of said longitudinal side beams 17, adjacent the end edges of the rearmost of said trap-doors, are pulleys 24, which are in horizontal alignment with said pulleys 20 and 22. Said trap-doors 15 and 16 are each secured near their side edges to suitable transverse rods 25, the outer ends of which work in corresponding lateral perforations in the longitudinal side beams 17 of said platform 14. Journaled in corresponding lateral perforations in said longitudinal side beams 17, adjacent the outer side of the rearmost of said trap-doors, is a transverse rock-shaft 26, provided with a lever 27 at one end. Secured to the bottom of said platform near the corner adjacent said rock-shaft and lever is a longitudinal block 28, and secured at one end to the inner side of said block and at its opposite end to said rock-shaft 26 is a spring 29, the function of which will be shown. Said block is provided at its outer end with a bearing 30, in which is journaled a pulley 31. Working laterally

through the outer part of said bearing is the inner eyed end of a transverse controlling-rod 32, the outer free end of which works through a corresponding lateral perforation 5 in the adjacent side beam 17 of said platform 14 and is adapted to engage the under side of said lever 27. Said controlling-rod 32 is provided with a coil-spring 33 and has secured in its inner eyed end one end of a cord or rope 34, which works over said pulley 31. Hinged at their outer ends to the inner faces of said side beams 17, near their rear ends, are plates 35, and secured to the inner perforated ends of said plates are the ends of short ropes 15 or cables 36, bent in the form of loops, which are adapted to hook over pins 37, extending upward from the periphery of said rock-shaft 26. Secured to the ends of the foremost of said trap-doors, near its inner side, by staples 20 or other equivalent means are the inner ends of chains 39. Said chains pass up over said pulleys 20, journaled near the inner faces of said side beams 17 of the platform, thence downward under said pulleys 22, 25 journaled to the ends of said door 16, thence upward over pulleys 24, journaled to the under sides of said side beams 17, thence horizontally rearward between said plates 35 and 30 guide wires or bars 40, two secured around and near each end of the rearmost of said transverse rods 25 at their inner turned ends and hooked over the tops of bearings 41, secured to the under faces of said side beams 17, near their rear ends, and thence upward 35 and are wound around a transverse shaft 42, journaled in bearings 43, secured to the rear edges of the innermost of said vertical beams 2. Said shaft is provided at its front end with a ratchet 44. Said ratchet is controlled by a 40 dog 45, fulcrumed at its inner end to the outer side of the adjacent vertical beam 2. A crank of any suitable construction may be employed to put said shaft 42 in rotation, when the chains wind around said shaft and 45 operate to close the trap-doors 15 and 16. The operator then pulls down on the free end of said lever 27, which effects a partial rotation of said rock-shaft 26, causing the cords or ropes 36 to wind around same and throw 50 the said clutches in engagement with said chains 39, which prevent said chains from slipping back or forth. Before throwing the free end of said lever 27 down to its lowest position it is necessary that the operator pull on the free end of said rope or cord 34 and draw the controlling-rod 32 inward out of the path of the lever. When the free end of the lever is thrown down to its lowest capacity, the operator releases the cord or rope 34, when 55 the contraction of said coil-spring 33, secured around said controlling-rod 32, throws the same outward in its normal position, its outer end engaging with the upper side of said lever, holding it in its last position.

60 To open the trap-doors, the operator pulls

on the free end of said rope 34, which releases the outer end of said controlling-rod 32 from engagement with said lever 27, when the action of said spring 33 effects a partial rotation of said rock-shaft 26, releasing the 7c clutches 35, through the medium of said short ropes or cables 36, from engagement with said chains 39, the weight of said trap-doors causing them to open. Said platform 14 is provided on its upper face, 75 near its rear side, with a dash 46. Said platform 14 is raised or lowered by means of four chains 47, two of which are secured to staples 48, secured in the upper faces and near the front ends of said side beams 17, 80 pass upward over pulleys 49, journaled in suitable bearing 50, secured on the tops and near the ends of the foremost of two or more transverse strengthening-beams 51, secured on the tops and near the ends of said longitudinal beams 3, thence horizontally rearward over pulleys 52, journaled in suitable bearings 53, secured on the top and near the ends of the rearmost of said transverse brace-beams 51, and thence downward and wind 85 around a main shaft 54, journaled near its ends in bearings 55, secured to the outer edges and near the lower ends of the rearmost of said vertical beams 2 and near its central part in bearings 56, secured to the 90 outer edges and near the lower ends of two central vertical braces 57, secured at their lower ends to said rear axle 5 and at their upper ends to the rearmost of said transverse strengthening-beams 51. The other 95 two chains are secured at their inner ends to staples 58, secured in the upper faces and near the rear ends of said side beams 17, pass upward over pulleys 59, journaled in suitable bearings 60, secured on the top and 100 rearmost of said transverse strengthening-beams 51, inward and adjacent said bearings 53, and thence downward and also wind around said main shaft 54. Horizontal rods 61, terminating in forks 62 at their rear ends, are secured at their front ends to the tops of said bearings 50, secured to the top of the foremost of said transverse strengthening-beams 51 and at their forked ends to the 105 tops of adjacent bearings 53 and 60, secured to the top of the rearmost of said brace-beams 51. Said main shaft 54 is provided intermediate of its length and between said vertical braces 57 with a circular enlargement or drum 63, to which is secured one 110 end of a draft rope or cable 64, adapted to wind and unwind around said drum. When in use, the said draft rope or cable works between a guide, which preferably consists of two vertical rollers 65, secured nearly contiguous between the outer ends of curved bars 66, secured at their inner ends to the outer sides of said vertical braces 57. Said main shaft 54 is provided near its front 115 end with a ratchet 67, adapted to be engaged 120

125 130

by a dog 68, fulcrumed at its inner end to the outer side of the adjacent vertical beam of said beams 2. Vertical plates 69, provided with elongated perforations 70, are 5 adjustably secured to the inner edges of said vertical beams 2. They are lowered to the ground when the machine is in operation and serve to anchor the machine and hold the platform 14 in position. It will be 10 obvious that said elongated perforations or slots facilitate the raising or lowering of the plates. Secured in the outer sides of said vertical beams 2, immediately under and in parallel apposition with said side beams 3, are longitudinal beams 71, and secured vertically to said beams 3 and 71 are bearings 72, in the lower ends of which are journaled horizontal rock-rods 73, one of which terminates at its extreme rear end in an eyed arm 74 and the other in a handle 75, carrying an integral inwardly-extending eyed arm 76. Secured at its ends in the eyes of said eyed arms 74 and 76 of said horizontal rock-rods 73 is an oblique transverse connecting-rod 77. Said rod 77 is provided with an eyed extension 78, in which is secured one end of a coil-spring 79, secured at its opposite end to the outer edge of the adjacent vertical beam 2. Said rock-rods 73 are provided 20 near their ends with vertical links 80, which are secured at their lower ends between the sides and near the outer ends of transverse guard-dogs 81, having secured between their sides and near their inner ends the lower ends of substantially vertical connecting-rods 82, suspended at their upper ends from supports 83 in the nature of rods bent partially around said longitudinal beams 3. Said connecting-rods 82 are suspended from 30 said supports in such a manner that their lower ends are susceptible of oscillation, the purpose of which will be shown. When in its normal position the free end of the handle 75 engages with a horizontal rearwardly-extending catch 84 of a transverse plate 85, secured to the outer edge of the beam of said vertical beams 2 adjacent said handle. In 40 this position the guard-dogs 81 are thrown outward sufficiently (see dotted lines, Fig. 5) to admit the passage of the platform 14 when hoisted. The free end of the handle 75 is then released from its engagement with said catch 84, when the action of said spring 79, through the medium of said transverse oblique connecting-rod 77 and said horizontal rock-rods 73, operates to throw said guard-dogs 81 inward, the inner ends of 50 which engage with the under side of said platform 14 and guard against accidental dropping of the same.

My invention is also equipped at its rear end with a rope or cable 86, which is secured to and wound around said main shaft 54 at one end, passes upward over a pulley 87, re- 60 movably secured in the rear end of a rear-

wardly-extending support 88, secured at its inner end to the rear end of the machine in any desired manner, and has secured to its opposite end a bucket 89 of ordinary construction loaded with rock or some other heavy material. The bucket of rock or other material serves to partly counterbalance the weight of the platform, so that when the same is unloaded and allowed to descend to the ground it will do so with a predetermined and uniform velocity. A tread-lever 90 is fulcrumed at its inner end to said rear axle 5 and is provided with a chain 91, which is secured to said axle immediately above the inner end of said lever, passes over a pulley 92, rigidly 80 connected to said main shaft 54 near its front end, and is secured to said lever at its free end.

Said machine is also preferably equipped at each upper corner with an oblique brace 85 95, which are secured at their upper ends to the outer sides of said side beams 3 and at their lower ends to the outer sides of said vertical beams 2 and at its rear lower part with oblique braces 96, which are secured at their 90 lower ends to the upper face of said rear axle 5 and at their upper ends to the inner sides of the rearmost of said vertical beams 2.

The operation of my device is as follows: The machine is placed where there is material to be hoisted and the reaches 12 removed. The platform is then lowered to the ground to receive the material to be hoisted, which may be drawn on the platform by scrapers of any desired construction. When the platform is sufficiently loaded, the main shaft 54 is put in rotation by a crank or other equivalent means. When the machine is operated without horse-power, a team is hitched to the free end of said draft-rope 64, secured to said 100 drum 63, and draws away from the machine, which operation effects the rotation of said main shaft and elevates the platform. When the platform is raised to the proper height, the ratchet 67, secured on the front end of said shaft, and dog 68 are thrown in engagement and hold the main shaft against reverse rotation and consequent dropping of the platform. To further guard against the dropping of the platform, the guard-dogs 81 110 may be thrown in engagement with the under side of the platform in the manner above described. The vehicle to receive the load is then driven under the platform, when the trap-doors are opened and the load dropped. 115 The doors are then locked again and the guard dogs thrown out of engagement with the platform, when the same is permitted to descend to the ground with a velocity controlled by the bucket 89 and its load. Should the operator desire the platform to descend to the ground at a slower velocity than usual when attained through the agency of the loaded bucket 89, rope or cable 86, and pulley 87, the tread-lever 90 may be employed. 120 125 130

Having described my invention, what I claim as new, and desire to secure by Letters Patent, is—

1. In a hoisting-machine, the combination of a truck; movable reaches, removably secured to the axles of said truck; main frame, consisting of vertical beams and a transverse beam at its front end, mounted on said truck; a platform, having side and end beams; doors, hinged in said platform; a rock-shaft, having extending from its periphery, near its ends, two pins, journaled in the side beams of said platform, adjacent the outer side of the rearmost of said trap-doors; a lever, secured to said rock-shaft near one end thereof; a block, secured longitudinally to the bottom of said platform, near the corner thereof adjacent said lever and rock-shaft; a spring, secured at its inner end to the periphery of said rock-shaft, and at its opposite end to one side of said block; a bearing, secured to the outer end of said block; a pulley, journaled in said bearing; a transverse controlling-rod, its inner end working through said bearing, and its opposite end through one of the side beams of said platform, near its rear end, and adapted to engage with said lever; a rope, secured at one end in the inner end of said controlling-rod and working over said pulley; plates, hinged longitudinally at their rear ends to the side beams of said platform; loops, secured in the free ends of said plates, and hooking over said pins of said rock-shaft; guide-wires, two secured near the inner face and rear end of each of said side beams of said platform, immediately over said plates; a transverse shaft, journaled to the rearmost of said vertical beams of said main frame; means for rotating and controlling said shaft; chains, secured at their inner ends to the ends of the foremost of said trap-doors, passing rearward over pulleys journaled near the inner faces of the side beams of said platform, then downward under pulleys journaled near the ends of the rearmost of said trap-doors, thence over pulleys journaled near the ends of the rearmost of said trap-doors, thence rearward between said clutches and said guide-wires, and thence upward, winding around said transverse shaft; a main shaft, journaled near the rear end of said machine, under said transverse shaft; chains, two secured at their front ends to the side beams of said platform near their front ends, passing upward over pulleys journaled over the top and near the front end of said frame, thence rearward over pulleys journaled over the top and near the rear end of said frame, and thence downward, winding around said main shaft, and two secured to the side beams of said platform near their rear ends, passing upward over pulleys journaled over the top and near the rear end of said frame, and thence downward, winding around said main shaft; drum, secured on said main shaft in- termediate of its length; a guide, consisting of two vertical rollers, secured near the rear end of said machine rearward of and opposite said drum; a draft-rope, secured at one end to said drum and working between said guide; a pulley, secured on said main shaft near its front end; a tread-lever, fulcrumed at its inner end to the rear axle of said truck, immediately under said last-mentioned pulley; a chain, secured to the free end of said tread-lever, passed over said pulley and secured to said rear axle at its opposite end; vertical plates, having elongated perforations, adjustably secured to the vertical beams of said frame; horizontal rock-rods, one terminating at its rear end in an eyed arm and the other in a handle carrying an eyed arm, journaled near the upper end of said frame; a transverse connecting-rod, connecting the rear ends of said rock-rods; a coil-spring, secured at one end near the rear end of said connecting-rod, and at its opposite end to one of the vertical beams of said frame; transverse guard-dogs, connected at their outer ends to said rock-rods, their inner ends held in movable suspension, the inner ends of said guard-dogs adapted to engage with the side beams of said platform when hoisted, substantially as shown and described.
2. In a hoisting-machine, the combination of a truck; movable reaches, removably secured to the axles of said truck; main frame, securely mounted on said truck; a platform, having side beams and transverse end beams; trap-doors, hinged in said platform; means for opening and closing said trap-doors; a main shaft, journaled, near the rear end of said machine; chains, two secured at their front ends to the side beams of said platform, passing over pulleys journaled near the front end and over the top of said frame, thence horizontally rearward over pulleys journaled over the top and near the rear end of said frame, and thence downward, winding around said main shaft, and two secured to the side beams of said platform near their rear ends, passing up over pulleys journaled over the top and near the rear end of said frame, and thence downward, winding around said main shaft; means for effecting the rotation of said main shaft; means for holding said main shaft against reverse rotation when said platform is hoisted; means for anchoring said machine in position; horizontal rock-rods, one terminating at its rear end in an eyed arm and the other in a handle carrying an eyed arm, journaled near the upper end of said frame; a transverse connecting-rod, connecting the rear ends of said rock-rods; a coil-spring, secured at its inner end near the rear end of said connecting-rod and at its opposite end to one of the vertical beams of said frame; transverse guard-dogs, connected at their outer ends to said rock-rods, their inner ends held in movable sus-

pension; a rearwardly-extending support, secured to said machine at its rear end; a pulley, secured to the upper free end of said support; a cable, secured to said main shaft at one end and passing over said pulley, and a bucket loaded with rock or other such material, secured to the free end of said cable, substantially as shown and described.

3. In a hoisting-machine, the combination of a truck; movable reaches, connecting with the axles of said truck; main frame, securely mounted on said truck; a platform having side and end beams; trap-doors, hinged in said platform; means for opening and closing said trap-doors; a main shaft journaled near the rear end of said machine; chains, two secured at their front ends to the side beams of said platform, passing over pulleys journaled near the front end and over the top of said frame, thence rearward over pulleys journaled over the top and near the rear end of said platform, and thence downward, winding around said main shaft, and two secured to the side beams of said platform near their rear ends, passing up over pulleys journaled over the top and near the rear end of said frame, and thence downward, winding around 60 said main shaft; means for effecting the rotation of said main shaft; means for holding said main shaft against reverse rotation when said platform is hoisted; vertical plates, having elongated perforations, secured to said 65 frame and adapted to anchor it in position; means for guarding against accidental dropping of the platform when hoisted, with means for maintaining a uniform velocity of said platform when ascending, substantially 70 as shown and described.
5. In a hoisting-machine the combination of a truck; main frame, mounted on said truck; a platform; trap-doors, hinged in said platform; means for opening and closing said 75 trap-doors; means for raising and lowering said platform; means for anchoring said machine in position; means for guarding against accidental dropping of the platform when hoisted, with means for maintaining a uniform 80 velocity of said platform when descending, substantially as shown and described.
6. In a hoisting-machine, the combination of a truck; main frame, mounted on said truck; a platform; trap-doors, hinged in said 85 platform; means for opening and closing said trap-doors; means for raising and lowering said platform; means for anchoring said machine in position; means for guarding against accidental dropping of said platform when hoisted, substantially as shown and described 90 for the purposes set forth.
7. In a hoisting-machine, the combination of a truck; main frame, mounted on said truck; a platform; trap-doors, hinged in said 95 platform; means for raising and lowering said platform with means for anchoring said machine in position, substantially as shown and described and for the purposes set forth.
- In testimony whereof I have signed my 100 name to this specification in the presence of two subscribing witnesses.
